UNITED STATES PATENT OFFICE.

HENRY J. BECK, OF TOLEDO, OHIO.

BOTTLE-CAPPING MACHINE.

1,278,829.

Specification of Letters Patent. Patented Sept. 17, 1918.

Application filed January 22, 1916. Serial No. 73,617.

To all whom it may concern:

Be it known that I, HENRY J. BECK, a citizen of the United States, and a resident of Toledo, in the county of Lucas and State of Ohio, have invented a certain new and useful Bottle-Capping Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to bottle capping machines. It particularly relates to a means for preventing the bottle from being pushed up into the capping die and being broken thereby.

20 The invention may be contained in different forms of bottle capping machines. What I have shown and described herein is merely a structure that I have selected as an example for the purpose of illustrating the 25 operation and construction of devices containing my invention.

Referring to the drawings, Figure 1 illustrates a sectional view of the parts of the bottle capping machine which operate upon the bottle to close and seal the cap on the bottle. Fig. 2 illustrates a sectional view of the elements illustrated in Fig. 1 when the bottle is forced to its extreme position relative to the sealing die.

35 1, Fig. 1, is a cam which operates upon a roller 2 secured to the lower end of a sleeve 3. The sleeve 3 is provided with a plunger 4 and with springs 5 which act upon the plunger. It is also provided with a frictional buffer 7 consisting of rods 8 which may be wedged into the space between the cone shaped nut 9 if the springs 5 are released too quickly. This construction is old and known in the art.

40 45 The bottle 10 is fed over the top of the plunger 4 in any suitable manner such as by means of a table, belt or other conveyer or feeding means. It passes beneath the sleeve 15 which may be secured to or formed integral with a plate or flange 16. The lower side of the flange or plate 16 is provided

with a downwardly extending flange 17 which is threaded to receive the ring 18. The ring 18 is provided with a conical opening 19 for guiding the top of the bottle to the die 20 which is located in a recess formed in the plate 16 or the point of union between the sleeve 15 and the plate 16. The die 20 is also provided with a conical or frustumal opening 22 which is shaped so as to compress the cap 23 about the lip of the mouth of the bottle. A plunger 24 is located within the sleeve 15. It has a flange 25 which abuts the lower end of the sleeve 15 and limits its downward movement. A compression spring 26 located intermediate the upper end of the sleeve 15 and the flange 25 yieldingly holds the plunger 24 down in the sleeve 15.

By my invention is provided a means for preventing the bottle 10 from penetrating beyond the sealing point in the die 20 which causes the bottle to break. I have provided a means for stopping the upward movement of the plunger 24 so that the springs 5 of the sleeve 3 will be compressed upon further upward movement of the sleeve 3 by the operation of the cam 1.

The plunger 24 is surrounded by a spring 26 the coils of which are, when in position to hold the plunger down, sufficiently close together so that when the plunger is raised slightly above the sealing point in the die 20, the coils will be compressed together, thus providing a stop for the plunger which in its upward movement will prevent the bottle 10 from entering the die 20 to an extent to cause the bottle to be broken.

Having thus described my invention, what I claim as new, and desire to secure by Letters Patent, is,—

1. In a bottle capping machine, the combination of a die for receiving the end of a bottle and pressing the edges of the cap around the lip of the bottle, a yielding means for forcing the bottle toward the die, a plunger for holding the cap upon the bottle, and a spring for yieldingly resisting the bottle from entering the die and positively preventing the bottle from entering the die beyond the sealing point of the cap of the bottle.

2. In a bottle capping machine, the combi-

nation of an annular die for receiving the end of the bottle and pressing the edges of the cap around the lip of the bottle, a yielding means for forcing the bottle toward the die, a spring pressed plunger for holding the cap upon the bottle, a spring surrounding the plunger for yieldingly resisting the

bottle from entering the die and for positively limiting its upward movement to prevent the end of the bottle from passing the 10 sealing point of the die.

In testimony whereof, I have hereunto signed my name to this specification.

HENRY J. BECK.
